UNITED STATES PATENT OFFICE.

FRED VERNE HART, OF LYNN, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

FEED MECHANISM.

1,352,748.

Specification of Letters Patent. Patented Sept. 14, 1920.

Application filed April 27, 1918. Serial No. 231,159.

To all whom it may concern:

Be it known that I, FRED V. HART, a citizen of the United States, residing at Lynn, in the county of Essex and State of Massachusetts, have invented certain new and useful Improvements in Feed Mechanism; and I do hereby declare the following to be a full, clear, and exact description of the invention, such as will enable others skilled 10 in the art to which it appertains to make and use the same.

This invention relates to mechanisms for feeding articles or pieces of material, and it has special reference to mechanisms for 15 feeding pieces of sheet material that are of wedge-shaped or uniformly tapering cross-section, such as the ordinary dinked or polygonal wedge-lifts employed in the formation of shoe-heels.

20 In a copending application, Ser. No. 136,935, filed December 14, 1916, by the present applicant, a feed-mechanism is disclosed which is adapted to successively eject or feed wedge-shaped lifts from the bottom 25 of a rotatable magazine in which the lifts are stacked in alternating face-to-face relation, that is, with their thick and thin ends together. The magazine is periodically given a half turn, whereby the successive 30 lifts ejected therefrom are caused to occupy similar positions with respect to their tapers.

One of the objects of the present invention is to provide a feed-mechanism of modified construction and operation which shall be adapted to accomplish a general result similar to that of the structure in the above indicated copending application, *i. e.*, feeding wedge-lifts or the like from a stack in 40 which they are alternately arranged, in such a manner that they shall occupy similar positions with respect to their tapers, but which shall attain the desired end by successively removing the lifts from the stack 45 and subsequently rotating them in their own planes into similar positions, in lieu of rotating the magazine prior to the ejection, as in the structure of the application referred to.

50 In accordance with the present invention, one of the features, through the agency of which the above object is accomplished, comprises a stationary magazine in which wedge-lifts are stacked in alternate relation and from which the lifts are success-

sively removed by means of a picker which picks up the lifts and transfers them to a position of discharge, during which transfer, the lifts are rotated through certain angles in substantially their own planes to 60 bring the lifts, as discharged, into similar positions with respect to their tapers. Other objects and features of the invention will become apparent from the following description of the preferred embodiment thereof 65 illustrated in the accompanying drawings.

Obviously, the invention is not in any sense restricted to the particular structure and operation shown and described, as many 70 modifications may be made therein within the spirit and scope of the invention. Broadly considered, the invention is not restricted to acting upon tapering or wedge-shaped articles but is applicable to articles 75 of other configurations, which are alternately arranged, and, for one reason or another, are desired to be fed into similar positions with respect to some characteristic or distinguished feature.

80 The invention will be best understood by reference to the accompanying drawings which illustrate the preferred embodiment thereof, in which; Figure 1 is a view in side elevation of a machine constructed in accordance with the present invention; Fig. 2 is a view in rear elevation of the apparatus shown in Fig. 1; Fig. 3 is a plan view of a portion of the apparatus, particularly illustrating the picker in position to seize a lift 85 in the magazine; Fig. 4 is a plan view, partially in section along section line 4-4 of Fig. 1, of that portion of the apparatus illustrated in Fig. 3 and showing the relationship of parts when the picker is in position to deposit a lift upon the conveyer; and Fig. 5 is a fragmentary view, partially in front elevation and partially in vertical section, of the picker in position when it is 90 about to release and deposit a lift.

95 Referring to the drawings, the apparatus shown comprises a frame 10 upon which the various parts and operating mechanisms of the machine are mounted; a magazine 12 for containing a plurality of wedge-shaped lifts W which are stacked therein in superposed face-to-face relation, with their thick and thin ends alternating; a conveyer 14 that is operated step-by-step and to which the lifts in the magazine are successively 100 105 110

transferred and upon which they are deposited; a picker 16 for picking up the successive lifts in the magazine and retaining them under control while being transferred to the conveyer; a supporting arm 18 that is pivotally mounted at one end and carries the picker 16 at the other, and which is adapted to be swung back and forth to actuate the picker from a position over the 10 magazine to a position above the conveyer; operating mechanism including an actuating lever 20 for raising and lowering the picker with respect to its swinging supporting arm to permit it to remove a lift from the magazine and deposit it upon the conveyer; operating mechanism, including a chain 22, for partially rotating the picker in opposite directions during the successive transferring movements from the magazine to the conveyer, whereby the alternately stacked lifts in the magazine are caused to occupy similar positions when deposited upon the conveyer; and a plurality of stops 24 that are adapted to automatically release the picker 25 in its discharging position above the conveyer, whereby the lifts are deposited thereon.

The frame 10, which supports the various parts and operating mechanisms of the apparatus, comprises side pedestals 26 and 28 upon which is mounted a cross plate 30 that supports the magazine 12. The side pedestals also support an upright bracket 32 upon which the swinging arm 18 is pivotally positioned.

Power is supplied to the machine continuously from a suitable source through a belt 34 that engages a pulley 36 which is fixed to a power and cam shaft 38, said shaft having bearings in the side pedestals 26 and 28. The shaft 38 is provided with a plurality of cams 40, 41 and 42 that are rigidly secured thereto, and also with a fixed gear 44 that meshes with a co-operating gear 46 that is rigidly secured to a sleeve 48 that is fastened to an auxiliary shaft 50 having bearings in the side pedestals 26 and 28. The sleeve 48 also carries a gear 52 that co-operatively engages a gear 54 that conveniently forms a 45 part of a sleeve 56 which is loosely mounted on the shaft 38. The sleeve 56 is provided with a cam 58. The gearing, just described, serves to reduce the speed of operation of the cam 58, and as designed, said cam is rotated 50 at one-half the speed of operation of the cams 40, 41 and 42, for a purpose that will hereinafter appear.

The magazine 12 for holding wedge-lifts W in alternating stacked relation comprises 60 a plurality of upright stationary angle members 60 and 62, and a movable clamping member 64, all of which are mounted on the cross-plate 30 and are adjustably positioned in a suitable manner in order to accommodate 65 lifts of different sizes. The movable

clamping member 64 is pivotally mounted upon a pin 66 and is provided with a lever arm 68 having a lost-motion pin-and-slot connection with one arm of a bell-crank 70, the other arm of which carries a roll 72 that 70 co-operatively engages the cam 42 by means of which the clamping member 64 is actuated. A spring 74 is attached to the clamping member 64 and tends to maintain the roll 72 in engagement with the cam 42. 75

The upper end of the clamping member 64 is preferably provided with small teeth 75 to assist in firmly clamping the upper lifts W in the stack, and the upper inner edges of the angle members 60 and 62 and 80 the clamping member 64 are provided with bevels 76 in order that the uppermost lift shall be loosely positioned so that it may be removed by the picker, as will be hereinafter more fully pointed out. 85

The stack of wedge-lifts W is supported upon a movable follower 78 that is secured to a follower rod 80, the lower end of which is provided with an annular guide bracket 82, the ends of which have sliding engagement with a plurality of guide rods 84 that are suitably secured to the frame. In order to raise the follower 78 and the lifts supported thereon, a flexible cord or other suitable member 86 is attached near the lower 95 end of the follower rod 80 and passes over pulleys 88. A weight 90 is attached to the other end of the cord and constantly tends to raise the follower 78 and lifts supported thereby. 100

To prevent the elevation of the stack of lifts until such time as desired, the cam 42 is so designed as to normally maintain the clamping member 64 in firm clamping engagement with the upper lifts in the stack, 105 and to effect a temporary release thereof at each cycle of operation in proper timed co-operation with the operation of the picker to permit the lifts to be raised into engagement with the picker, as will be hereinafter set forth. 110

While the machine of the present invention is broadly adapted to feed lifts from a stack in which they are alternately arranged, in such manner that they shall occupy similar positions with respect to their tapers, the machine is particularly intended to be utilized as a unit of a machine or system for building heels, such, for instance, as set forth in Letters Patent No. 1,286,472 115 granted Dec. 3, 1918, to Erastus E. Winkley. The machine of the application referred to comprises a link conveyer which is actuated step-by-step through a series of stations at which lifts of uniform thickness are 120 deposited in superposed relation to build flat heels. By the substitution of the machine of the present invention at one of the stations, the apparatus of the above mentioned application may be employed to build 125 130

wedge heels, in which case the present machine is arranged and adapted to successively feed and deposit wedge-lifts upon the previously assembled lifts on the conveyer, 5 as will be understood.

The conveyer 14, therefore, will conveniently serve the purpose of the conveyer of the aforesaid heel-building machine upon which heels are assembled and the wedge-lifts W are deposited. The conveyer 14 comprises a series of links 92 that are pivotally connected together in a suitable manner by means of pins 94. The conveyer 14 is preferably actuated step-by-step by any 10 suitable means (not shown), and, at each step of its actuation, a link is presented in position to receive a wedge-lift W from the magazine 12.

The alternately stacked wedge-lifts W in 20 the magazine 12 are successively seized and removed therefrom by the picker 16, which transfers them through the swinging of the arm 18 to a position above the conveyer 14, whence they are deposited upon the previously 25 assembled lifts L upon the successive links thereof.

The picker 16 (Fig. 5) comprises a sleeve 96 that is longitudinally movable and rotatable within the outer end 98 of the swinging arm 18, said sleeve being provided with a central recess through which an actuating rod 100 loosely projects. A plurality of pointed claws 102 are pivotally mounted in spaced relation at the lower end of the 35 picker sleeve 96 and have coöperative engagement with the lower end of the rod 100, through the agency of which the claws may be positively operated, either to force the claws outwardly to impale a lift or to withdraw them to release the lift. Near the 40 lower end of the rod 100, a collar 104 is provided which is adapted to engage a shoulder 106 in the sleeve 96 under certain conditions, whereby the picker, as a whole, may be raised in position. The upper end of the 45 sleeve 96 (Figs. 1 and 5) is provided with a recess 108 to receive a spring 110, the lower end of which abuts against a shoulder 112 and the upper end of which engages a collar 114 that is pinned to the rod 100. The 50 spring 110 is of sufficient strength to normally maintain the collar 104 in engagement with the shoulder 106 of the sleeve 96, but which is adapted to yield under predetermined 55 conditions when the rod 100 is depressed to cause the claws 102 to impale a lift.

For the purpose of retaining a lift W that is seized or impaled by the claws 102, 60 the sleeve 96 is provided with a spring actuated latch 116 that is adapted to coöperate with and restrain the collar 114 when said collar and associated rod 100 are depressed. The latch 116 is pivotally mounted upon a 65 pin 118 and is provided with a tail piece

120 that extends laterally into such position that it may be engaged at predetermined times by the one or the other of the stops 24, whereby the latch 116 is released.

As hereinbefore stated, the picker 16 is 70 adapted for rotative movement to turn the successive lifts in partial rotations in opposite directions and, to produce such movement, a sprocket 122 is supported in the arm 18 and connected to the sleeve 96 by a 75 spline 124 so as to rotate the sleeve without interfering with the longitudinal movements.

To enable the picker 16 to be actuated to-and-fro between the magazine 12 and 80 the conveyer 14, said picker is mounted upon the free end of the swinging supporting arm 18, which is pivotally mounted upon a sleeve 126 that projects through and is carried by arms 128 and 130 of the upright bracket 32. The sleeve 126 is rotatably mounted within said arms and is supported by means of a collar 132 that is pinned thereto and rests upon a portion 134 of the supporting arm 18. The swinging 90 arm 18 is actuated back and forth through the agency of a lever 136 that is secured thereto, the outer end of which has a universal connection 138 with a link 140 that has another universal connection 142 with the upper end of an arm of a bell-crank 144 having another arm that carries a cam roll 146 which coöperatively engages the cam 40. A spring 148 acts upon the bell-crank 144 to maintain said cam roll in engagement 100 with said cam.

A picker 16 is raised and lowered bodily with respect to the supporting arm 18, and the claws 102 thereof are actuated by means of the rod 100 and the actuating lever 20 in 105 a manner to be now described. The actuating lever 20 is pivotally mounted intermediate its ends upon an upwardly projecting lug 150 that constitutes a part of the picker supporting arm 18. The outer end of the 110 lever 20 is bifurcated and engages the opposite sides of a spool 152 that is secured to the upper end of the rod 100, while the opposite end of the lever 20 has a pivotal connection to a connecting rod 154 that projects loosely through the sleeve 126. The lower end of the rod 154 is connected to one arm of a bell-crank 156, the other arm of which carries a roll 158 that coöperatively 115 engages the cam 41.

It will be understood that, during each cycle of operation of the machine, the picker 16 is depressed into position to be engaged by the upward movement of the uppermost lift W in the magazine 12, the 125 claws 102 are forced outwardly to impale and seize the lift, after which the picker is raised bodily, and, by the swinging movement of the supporting arm 18, is transferred to a position above the conveyer 14. 130

Thereupon, the picker is bodily depressed until the lift is placed upon the conveyer, after which the claws are withdrawn and the lift released. The picker is then again elevated and moved back to its initial position by the swinging movement of the supporting arm 18.

Inasmuch as the wedge lifts W are alternately stacked in the magazine 12 in such position that their breast edges are parallel to the direction of movement of the conveyer, it is manifest that the picker 16 and the successive lifts which are seized thereby must be rotated approximately through quarter turns in opposite directions and in substantially the planes of the lifts during the transferring movement in order that the lifts, as deposited upon the conveyer, shall occupy similar positions with respect to their tapers and breast edges. This rotative movement is effected through the agency of the chain 22 and the sprocket 122, as has been hereinbefore mentioned. The chain 22, not only coöperates with the sprocket 122 upon the picker, but also with a sprocket 162 that is pinned on the rotatable sleeve 126. The lower end of said sleeve is provided with a fixed segment 164 that meshes with a reciprocating segment 166 that is pinned upon a bolt 168 that projects downwardly from an arm 170 which is integral with the upright bracket 32. The segment is provided with an arm 174 on the opposite side of its pivotal support which 35 has a universal connection 176 with a link 178 having a universal connection 180 with the upper end of an arm, constituting a part of a bell-crank 182, the other arm of which carries a roll 184 that coöperatively 40 engages the cam 58.

As has already been set forth, the cam 58 is adapted to rotate at one-half the speed of the other cams on the shaft 38, so that although the picker 16 is rotated first in one direction and then in the other, only one of such rotations occurs at each cycle of operation of the machine. Moreover, the cam 58 is so designed and positioned with respect to the other cams that each rotation 50 of the picker 16—that is, first in one direction and then in the other—occurs during the transferring movement of the picker from the magazine 12 to the conveyer 14. It is evident, therefore, that as the alternately stacked lifts W in the magazine 12 are successively transferred to the conveyer, they are alternately rotated in substantially their own planes in opposite directions, whereby the desired similarity in position 55 of the wedge-lifts W upon the conveyer is attained. By reason of the timing of the rotative movements of the picker, as just set forth, no rotation of the picker is effected during the return movements thereof to the magazine.

The release of the picker 16 and the discharge of the lifts W seized by the claws 102 is effected automatically by means of the stops 24 upon an arm 188 that projects from the upright bracket 32 in a position 70 substantially over the conveyer 14. These stops 24 are adjustable in height and are so located as to alternately engage the laterally extending tail piece 120 of the latch 116 as the picker 16 is depressed to deposit 75 a lift upon the conveyer.

Having described the construction and operation of the various parts and mechanisms of the machine, a description of a complete cycle of operation of the apparatus will be given in order that the relative time relation of the component mechanisms may be more clearly understood.

Assuming the various parts of the apparatus to occupy the positions shown in Figs. 85 1, 2 and 3, and that power is supplied to the machine, the operation thereof is as follows:

The cam 41, through the mechanism controlled thereby, serves to lower the actuating rod 100, which, through the agency 90 of the spring 110, yieldingly depresses the picker bodily to its lowermost position over the center of the magazine 12, in which position the lower end of the picker sleeve 96 lies in the plane of the upper end of the 95 magazine. At this time, the cam 42, through its associated mechanism, effects the temporary release of the clamping member 64 of the lift magazine 12, whereupon the follower 78 and the stack of lifts 100 supported thereon is raised until the uppermost lift engages the lower end of the picker, whence the movement thereof is arrested. Having thus brought the uppermost lift W into engagement with the lower end of the 105 picker, the continued downward movement of the actuating rod 100 yieldingly maintains the sleeve 96 in engagement therewith through the agency of the spring 110 and positively forces the claws 102 outwardly, 110 whereby the uppermost lift is impaled thereon and seized thereby. During this operation, the collar 114 on the rod 100 is depressed sufficiently to enable the latch 116 to become operative to retain the claws in 115 their outward seizing position.

Subsequently, the cam 41 effects the bodily elevation of the picker 16 with the lift impaled thereon. The picker 16 and lift is then transferred to a position over the conveyer 14 by a swinging movement of the picker supporting arm 18, which is effected by means of the cam 40. During the transferal of the picker and lift to this position, the cam 58, through its associated 120 mechanism, effects a clockwise rotation of the picker and lift, whereby the lift is rotated in its own plane substantially a quarter turn and is brought into the position indicated in Fig. 4, this position being such 125 130

that the tail piece 120 of the latch 116 is directly above one of the stops 24, as shown in dotted lines in Fig. 3. The cam 41 then causes the picker 16 to be lowered until the 5 lift is placed upon the previously assembled lifts upon the link of the conveyer 14. Just at the time when the lift is placed upon the conveyer, the tail-piece 120 of the latch 116 is brought into engagement with the stop 10 24 immediately beneath it, and the latch is thereby released. Fig. 5 illustrates the picker on the point of being released by one of the stops 24. Upon the subsequent raising of the actuating rod 100, through the 15 agency of the cam 41 during the initial part of which action the sleeve 96 is held down in engagement with the lift being deposited by means of the spring 110, the claws 102 are withdrawn from the lift, which is therefore 20 deposited in its position upon the conveyer. As the upward movement of the actuating rod 100 continues, the collar 104 is brought into engagement with the shoulder 106 of the sleeve 96 and the picker is therefore 25 bodily raised. The picker 16 and its supporting arm 18 are then swung back to their initial position, as illustrated in Figs. 1, 2 and 3, it being noted that during this return movement no rotation of the picker 30 is produced, by reason of the fact that the cam 58, which controls such rotation, is driven at only one-half the speed of the other cams.

This cycle of operation is repeated as the 35 operation of the machine continues, except that during the next cycle, and each alternate one, the picker is rotated in a counter-clockwise direction instead of clockwise as just described, whereby the next wedge-lift 40 W and succeeding alternate lifts, which occupy a reversed position in the stack, are turned in their own planes in the opposite direction and are placed on the conveyer in similar positions with respect to their tapers 45 and breast edges. By reason of the opposite direction of rotation of the picker, just referred to, the tail-piece 120 of the latch 116 is brought into position over the other stop 24 which, during the lowering movement 50 of the picker, effects the release of the claws 102 in the same general manner as already set forth.

Having described the construction and operation of the preferred embodiment of 55 the present invention, that which is claimed as new, is:—

1. Blank feeding mechanism having, in combination, a holder for a stack of blanks, and mechanism acting to transfer the blanks 60 successively from the stack to a point of delivery and to impart varying angular movements to the blanks in substantially the planes of their faces.

2. Blank feeding mechanism having, in 65 combination, a holder for a stack of blanks,

a picker, means for actuating the picker to transfer the blanks successively from the stack to a point of delivery, and means for imparting varying rotary movements to the picker.

70

3. Blank feeding mechanism having, in combination, a holder for a stack of blanks, a picker, a picker carrier, means for actuating the picker to take the blanks successively from the stack and for actuating the 75 carrier to transfer the blanks to a point of delivery, and means for imparting varying rotary movements to the picker in the carrier.

4. Blank feeding mechanism having, in 80 combination, a holder for a stack of blanks, a picker, means for actuating the picker to transfer the blanks successively from the stack to a point of delivery, and means for rotating the picker alternately in opposite 85 directions.

5. Blank feeding mechanism having, in combination, a holder for heel lifts arranged in a stack with their breast edges facing alternately in opposite directions, and mechanism for transferring the blanks successively from the stack to a point of delivery and for rotating the blanks in the planes of their faces to deliver the blanks with their breast edges facing in the same direction.

95

6. Blank feeding mechanism having, in combination, a holder for heel lifts arranged in a stack with their breast edges facing alternately in opposite directions, a picker, means for actuating the picker to transfer 100 the blanks successively from the stack to a point of delivery, and means for imparting rotary movements to the picker to deliver the blanks with their breast edges facing in the same direction.

105

7. Blank feeding mechanism having, in combination, a holder for heel lifts arranged in a stack with their breast edges facing alternately in opposite directions, a picker, means for actuating the picker to transfer 110 the blanks successively from the stack to a point of delivery, and means for rotating the picker alternately in opposite directions to deliver the blanks with their breast edges facing in the same direction at right angles 115 to the breast edges of the blanks in the stack.

8. Blank feeding mechanism having, in combination, an intermittently fed conveyer upon which heel lifts are assembled in superposed relation, a holder for wedge lifts arranged in a stack with their breast edges facing alternately in opposite directions, and picker mechanism acting to transfer the lifts successively from the stack to the conveyer and to impart varying angular movements to the blanks to bring their breast edges into alinement with those of the lifts upon which they are deposited.

120

9. Blank feeding mechanism having, in 125

combination, an intermittently fed conveyer upon which heel lifts are assembled in superposed relation, a holder for wedge lifts arranged in a stack with their breast edges 5 normal to those of the lifts on said conveyer and facing alternately in opposite directions, and picker mechanism acting to transfer the lifts successively from the holder to the conveyer and to rotate the lifts alternately in opposite directions to bring their breast edges into alinement with those of the lifts upon which they are deposited.

10. A feed-mechanism for tapering articles of sheet material having, in combination, means for holding a stack of such articles with their thick and thin ends alternating, and means for picking the successive articles successively from the stack and rotating them in the planes of their faces 15 so as to bring them all into similar positions with respect to their thick and thin ends.

11. A feed-mechanism for tapering articles having, in combination, means for holding a stack of said articles in alternately arranged face-to-face relation, and means for picking the articles successively from the stack and rotating them in substantially the planes of their faces into similar positions 20 with respect to their tapers.

12. A picker for seizing a piece of stock, comprising a support, a sleeve carried thereby and longitudinally movable therein, claws pivotally mounted at one end of said sleeve, a rod movable within said sleeve and 35 connected to said claws, a spring interposed between said sleeve and said rod, and means for actuating said rod to move said sleeve through said support through the action of said spring and to positively operate said claws.

13. A stock-handling machine having, in combination, a support, an axially rotatable and longitudinally movable picker carried thereby, means for longitudinally actuating 45 said picker, and means for rotating said picker about its axis while permitting longitudinal movements thereof.

14. A stock-handling machine having, in combination, a supporting member and a picker carried thereby and longitudinally movable therein comprising a sleeve having a central recess, claws pivotally mounted at one end of said sleeve, positive means projecting through said recess for operating 50 said claws, means for restraining said claws in their operative position, means tending to move said sleeve through said supporting member to release said claws, and means for rendering said restraining means inoperative.

15. A stock-handling machine having, in combination, a supporting member and a picker carried thereby, and longitudinally movable therein comprising a sleeve having 60 a central recess, claws pivotally mounted

upon said sleeve, a rod extending through said recess into operative engagement with said claws, resilient means acting upon said rod and said sleeve for normally maintaining the claws in inoperative position, 70 means for actuating said rod to move said sleeve through said resilient means and to operate said claws, and means for restraining the claws in their operative position.

16. A stock-handling machine having, in combination, a supporting member and a picker carried thereby, comprising a slideable sleeve having a central recess therein, claws pivotally mounted at one end of said sleeve, a rod loosely projecting through said recess into operative engagement with said claws and having means for engaging said sleeve wherebv it may be raised, a spring interposed between said rod and said sleeve, means acting through said rod, for causing 80 said spring to depress said sleeve, and for positively operating said claws, and means carried by said sleeve for restraining said claws in their operative position while permitting movement of said sleeve with respect to said supporting member.

17. A stock-handling machine having, in combination, a magazine for holding a stack of pieces, means for supporting the stack of pieces tending to elevate them in said magazine, means normally restraining the operation of said elevating means, a movable picker for seizing the uppermost piece in the stack, means for moving said picker over said magazine in position to be engaged by the uppermost piece as the stack is elevated, means for temporarily releasing said restraining means to permit the stack to be elevated into engagement with said picker, and means for causing said 100 picker to seize the uppermost piece in the stack.

18. A stock-handling machine having, in combination, a movable support, a picker slidably and rotatably mounted thereon, said 110 picker comprising claws pivotally mounted at one end thereof, means for depressing said picker into engagement with and for causing said claws to seize a piece of stock, means for restraining said claws in operative position, means for moving said support and picker, means for rotating said picker, and means for releasing said restraining means to permit the release of said claws from the piece of stock.

19. Blank feeding mechanism having, in combination, a movable conveyer upon which heel lifts are assembled in superposed relation, a holder for wedge lifts arranged in a stack with their breast edges 125 facing alternately in opposite directions, and means for transferring the lifts successively from the stack to the conveyer and for rotating them about axes within their boundaries in substantially the planes of their 130

faces to bring their breast edges into alignment with those of the lifts on which they are deposited.

20. A feed mechanism for tapering articles of sheet material having, in combination, a stationary magazine for holding a stack of such articles with their thick and thin ends alternating, means for transferring the articles successively from the stack to a point of delivery, and means for rotating said articles in the planes of their faces and about axes within their boundaries to bring them all into similar positions at the point of delivery.

21. A feed mechanism for tapering articles having, in combination, a stationary magazine for holding a stack of said articles in alternately arranged face-to-face relation, and means for transferring the articles successively from the stack to a point of delivery and for rotating the articles in substantially the planes of their faces and about axes within their boundaries during the transferring operation to bring them into similar positions at the point of delivery.

22. A feed mechanism for tapering articles having, in combination, a magazine for holding a stack of said articles disposed in alternate relation, a picker, a picker carrier, means for actuating the picker to take an article from the magazine and for actuating the carrier to transfer the article to a point of delivery, means for rotating the picker during each transferring operation to bring the articles into similar positions,

and means for actuating the picker to deliver the articles.

23. A stock-handling machine having, in combination, a stationary holder for a stack of tapering pieces of stock disposed in alternate relation, a picker for seizing the successive uppermost pieces in the stack and transferring them to a point of delivery, means for restraining the picker in its seizing position, means for rotating the picker in opposite directions during the successive transferring movements to bring the pieces into similar positions with respect to their tapers, and a plurality of stops above the delivery point and acting successively to release said restraining means.

24. A stock-handling machine having, in combination, a stationary magazine for holding a stack of tapering pieces disposed in alternate face-to-face relation, means for feeding the stack upwardly through the magazine, and means for successively removing the uppermost pieces from the magazine and delivering them in similar positions with respect to their tapers.

25. A stock-handling machine having, in combination, means for supporting a piece of stock, a rotatable picker for seizing the stock, an arm for carrying said picker, a pivotal support for said arm, means for swinging said arm and picker about said pivotal support, and means for actuating said pivotal support to effect rotative movements of said picker.
